CONVERTIBLE MACHINE CARRYING CASE
AND WORKSTAND

Philip Ayotte, Bridgeport, Conn.

Application July 23, 1949, Serial No. 106,370

13 Claims. (Cl. 312—30)

1

This invention relates to portable machine cases and particularly such cases designed to be convertible to work stands for supporting machines in operative position in such a way that an operator may sit before the stand and operate the machine in a comfortable, practical and convenient manner. Cases of this type have particular utility in connection with sewing machines and the invention is consequently illustrated and described with relation to a sewing machine.

Conventional practice in the mounting of sewing machines has been either to attach the machine to a permanent article of furniture or work stand, known as a console, or to provide a portable machine which must be placed on some stand or article of furniture for use. The console structure is solid and firm, of convenient height, provides a smooth working surface, and is generally satisfactory during operation, but is bulky, requires excessive storage room when not in use, is particularly inconvenient in small apartments, and cannot be moved readily for use at various places. The portable machines are readily stowed when not in use, can be moved about freely from place to place, but are not sufficiently convenient during operation to suit the needs of a person who makes frequent use of such equipment. For example, most supports or tables found in the home which are sufficiently sturdy and at the same time provide knee room, raise the portable machine too high for comfortable operation. The portable machine must also have a base of substantial thickness to house the shuttle and operating mechanism, and which projects above the table or other supporting surface so that the working surface is made awkwardly irregular thereby.

It is an object of this invention, therefore, to provide a portable machine case of such character that it will house the machine for stowage in a small space and can be carried readily from place to place, but which also includes structure such that it can be opened up to form a work stand of unusual solidity which not only provides knee room for a seated operator, but which also holds the machine at the proper level for convenient and comfortable operation and exposes a large smooth work surface uncomplicated by a machine base.

Other features and advantages will hereinafter appear.

In the drawing:

Figure 1 is a front elevation of the cabinet of the invention showing the same expanded to form a work stand.

Fig. 2 is a fragmentary left end elevation of the device of Fig. 1.

2

Fig. 3 is a right end elevation of the device of Fig. 1, but showing the machine in lowered position and the work leaf folded.

Fig. 4 is a fragmentary front elevation, partially in section, of the cabinet of the invention with the work leaf folded and with one support member extended and the other swung to stowed position, the support members being also shown in an intermediate partially swung position by broken lines.

Fig. 5 is a front elevation, partially in section of the device of Fig. 4 after swinging of the support members to stowed positions has been completed.

Fig. 6 is a perspective view of the device in entirely folded condition ready for stowage or transportation and with the housing resting on its back in carrying position.

Fig. 7 is a front elevation to a reduced scale of a modification of the device of the invention.

The machine cabinet of this invention comprises an open bottom housing 10 having a front wall 11, back wall 12, and side walls 13 and 14. A suitably apertured top wall 16 is provided with means such as hinges and latch devices of known construction for holding a sewing machine 18 either in operating position extending above the top wall 16 as shown in Fig. 1 or for permitting the machine to be swung down within the housing 10 to stowed position with its bottom surface 30 adjacent the back wall 12 thereof as shown in Fig. 3. Attached to the top 16 at one end thereof by hinges 20 is a work leaf 22 which is congruent with the top 16 and which may be opened out flush with the top 16 to provide a large convenient work space, or folded over the top 16 to overlie the same, cover the mounting means for the machine 18 and close any opening in the top wall 16 left by the machine when it is moved to the stowed position shown in Fig. 3. Up to this point, except for the open bottom of housing 10, the parts mentioned conform generally to the usual structure employed in sewing machine stands of the console type, and further description is consequently unnecessary.

Since the casing 10 is portable and will be carried and placed in various positions, a tensioning fastener 24, preferably of the toggle loop or trunk catch variety, is provided for lashing the leaf 22 firmly in place against the top 16 and preventing any shifting or rattling thereof during carrying of the device.

Connected to the bottom edge of wall 13 by hinges 32 are legs 32 and 34 which are united to form a single support member 35 for one end 55 of the housing 10 by a rung 36 connected to said legs near their free ends. To brace said legs and thus steady the left-hand end of the stand

against forward and backward shifting, there is provided a brace plate 38 of substantial height firmly fixed to the inner sides of the legs 32 and 34 near the top hinged ends thereof.

Connected to the bottom edge of end wall 14 by hinges 40 is a panel 42 forming a support member for the other end of the housing 10. The panel 42 preferably includes spaced feet 44 for a reason to be hereinafter explained.

As shown in Figs. 4 to 6 particularly, the support members 35 and 42 are swingable towards each other. When in stowed position the leg 32 lies just inside the front wall 11 with its outer surface flush with the bottom edge thereof and the leg 34 is in similar relation to the back wall 12. The panel 42 is designed so as to swing to a position lying between the legs 32 and 34, to fill the area between them, and to be flush with their outer surfaces and with the lower edges of the walls 11 and 12. In this way the support elements when in stowed condition form a smooth closure for the bottom opening of the housing 10. To retain the supports in the stowed position of Figs. 5 and 6 I prefer to provide the end of the panel 42 with a spring clip 46 which engages a projection 48 in the housing 10. By overlying the rung 36 and other parts connected thereto, the panel also retains the legs 32 and 34 in place. A finger notch 50 is preferably provided at the end of the panel 42 so that the same may be firmly gripped to withdraw the spring catch 46 from the projection 48 in setting up the stand.

In order that the portability and convenience of the stand may be kept at a maximum, its overall dimensions when folded as shown in Figs. 5 and 6 must be held to a minimum. With reference to the size of a standard sewing machine, the covering of the machine itself, while it must be first considered, is not the critical factor in the housing dimensions and may be largely disregarded. The length or side-to-side dimension of the housing 10 is first maintained as short as possible. The practical limit on shortening this dimension is fixed by the fact that the length of the housing determines the length of the supports 35 and 42. In order to maintain a convenient working surface height of about 30 inches which represents the sum of the length of support 35 and the height of the housing 10, the length of the housing cannot be reduced excessively without adding additional height to the housing which will in turn make the folded device thicker and more unwieldy for carrying. A certain advantage can be gained by adding the thickness of an end wall to each of the support elements, feet 44 in the case of panel 42, and notching the corresponding end walls as indicated by reference characters 13' and 14' to permit the supports to travel into flush position. In this way a slight shortening of the housing 10 is permitted without the necessity for an equal and undesired increase in housing height. Even when the optimum proportions for the housing have been achieved, it will be found that the knee of an operator seated before the stand will not ordinarily be able to pass below the lower edge of the front wall 11 of the housing 10. For this reason I provide said wall with a displaceable wall portion which can be moved aside when the machine is in use to provide such knee room. In the form shown in the drawing this portion is a door or panel 11a mounted on hinges 11b to swing outwardly to one side, the panel preferably being provided with any desired sewing accessory equipment such as pin cushions, spool holders,

scissors holders, or the like on its inner surface, and being held in closed position by any suitable snap catch (not shown).

The support members 35 and 42, when swung to supporting position as shown in Figs. 1 to 3, are firmly held against any further swinging by a diagonal brace 60 and a separating strut 70 (Figs. 1 and 2). The diagonal brace 60 is foldable and preferably consists of two rigid links 61 and 62 pivotally connected at one end of each by a hinge 63. The other end of link 61 is connected to the inside of end wall 14 by a hinge 64, while the other end of link 62 is pivoted on the rung 36. The link 61 is longer than the link 62 by enough to compensate for the spacing of the axes of rung 36 and hinge 64 when the parts are in stowed or portable position as shown in Figs. 4 and 5. After being swung to unfolded position, the foldable brace 60 is made rigid by the hook 65 which may be swung across the hinge joint between the links and is clamped in place preferably by a hand nut 66. The support 35 is thus braced and made a firm and rigid part of the structure. The strut 70 is also preferably foldable and consists of links 71 and 72 of about equal length pivotally connected at one end of each by a hinge 73. The other end of link 71 is pivoted to the inner surface of panel 42 near the free end thereof by a hinge 74, while the free end of link 72 is equipped with means for releasably engaging the rung 36. In the form shown this means is a downwardly opening hook 75 of a size to snugly engage the rung 36. If desired any suitable means may also be used for closing the mouth of the hook after the same is in place to prevent inadvertent dislodgement. A hook 76 and hand nut 77, similar to members 65 and 66 described above, are provided for locking the links 71 and 72 in position to form a rigid strut. When the strut 70 is extended and made rigid, and the hook 75 snugly fitted over the rung 36, the support 42 is also made a firm and relatively immovable part of the structure. I also preferably provide a projection on one part of the strut 70, for example as indicated by numeral 78 in Figs. 1 and 2, for engagement with a spring catch 79 on panel 42. Thus when the strut is folded the catch 79 will hold the same compactly against the panel until ready for use. The strut 70 is made foldable primarily so as to nest with the support 35 by fitting between the lower edge of the brace plate 38 and the rung 36 thereof when the parts are in stowed position as indicated by the dotted lines in Fig. 5.

It will be noted in Fig. 2 that the diagonal brace 60 and strut 70 are located near a vertical median plane between the front and back surfaces of the stand. This relationship of parts is significant in that the central positioning of the strut and brace elements provides adequate stiffness for the support elements 35 and 42 whether the stresses are applied near the front surface or the rear surface thereof, with consequent lack of any tendency for the working surface 16, 22 to swing or twist in a horizontal plane with relation to the position of the feet of the stand. At the same time the central positioning of parts 60 and 70 provides adequate room for the feet and legs of an operator so that she may sit close enough to the machine 18 for comfortable operation. To achieve both of these advantages to the fullest extent the attachment points of the brace 60 and strut 70 should never be removed from either corner of the stand by more than about two-thirds of the front-to-back dimension

of the stand, and neither should project forwardly of a vertical plane set back about one-third of said dimension from the front of the stand.

A handle 80 is provided in the middle of the front wall 11 of the housing 10 for carrying the device when in folded condition. This position is chosen for the handle in order that the machine 18 may be stowed and carried in the erect position which is preferred from the standpoint of preserving proper lubrication. The rear surface of the housing 10 is provided with feet 81 to prevent marring the rear surface of the housing 10 by contact with the supporting surface on which it rests. An electrical receptacle 82 mounted in the end wall 14 may be electrically connected with the driving motor (not shown) for machine 18 in the usual manner, and provides means by which an extension cord from the usual domestic electric supply outlet may be connected with the machine 18. The usual foot pedal (not shown) for controlling the speed and operation of the machine will be connected thereto by an electric conductor in a well known manner and will be projected from the open bottom of the housing 10 to a suitable place on the floor when the machine 18 is in use, and placed inside the casing for storage purposes on closing the housing as is customary with portable sewing machines.

The device as shown in Fig. 1 may be readily folded to portable size by first operating the conventional machine supporting means to release the machine and allow the same to swing down into the position of Fig. 3. The leaf 22 is then swung over the top of the housing and securely lashed by means of catch 24. Then, by grasping the handle 80, the stand and is readily tipped on its back so that the housing rests on feet 81. The nuts 66 and 77 and hooks 65 and 76 are then released, hook 75 is removed from rung 36, and the strut 70 is folded against the panel 42 and held there by engagement of projection 78 with spring catch 79. The diagonal brace 60 is folded, simultaneously drawing the support member 35 into place against the bottom of the housing 10 (Fig. 4) with the end of legs 32 and 34 seated in notches 14'. Swinging the panel 42 into position between the legs 32 and 34 nests the folded strut 70 and closes the housing 10. As the panel 42 is forced home the clip 46 engages projection 48 to hold all the parts in folded position, the panel 42 resting against the link 62 and thereby positioning the rung 36 which holds the legs 32 and 34 firmly seated in the notches 14'. Unfolding the device of Figs. 5 and 6 to provide the stand of Figs. 1 to 3 is accomplished by merely reversing the foregoing series of steps.

In Fig. 7 is illustrated a modified form of the invention in which the foldable diagonal brace 60 is replaced by a pair of foldable diagonal braces 60a and 60b. The foldable braces 60a and 60b are lengths of any suitable flexible material such as chain or wire rope, the chain form being shown in the drawing. The chain 60a is connected to rung 36 at one end and anchored on the side wall 14 of casing 10 at its other end. The chain 60b is connected to the panel 42 near the free end thereof and has its other end anchored on the side wall 13 of the housing 10. Any suitable conventional means such as adjustable anchors or turnbuckles (not shown) may be provided for properly adjusting the lengths of chains 60a and 60b. When the chains are set at the proper length, the strut 70 will be found to re-

main very slightly bent at hinge 73 when under the influence of the free lengths of the chains and with its end hooked over rung 36. By applying a slight downward force to the strut 70, 5 it may be made to serve as a toggle, and when the same is straightened and locked with hook 76 the chains 60a and 60b will be under slight tension. The whole undercarriage of the stand will then be found to set up into a firm and rigid 10 support for the housing 10 and machine 18. The foldable braces 60a and 60b occupy a vertical plane or planes situated similarly to the location of the plane of the foldable brace 60 of Fig. 2 or planes which correspond in all respects to the 15 principles for placing the bracing and strut elements discussed at length above. In all other respects the stand of Fig. 7 is preferably the same as the device of Figs. 1 to 6, most of the details having been omitted in this view for purposes of clarity.

In the interests of clearness and brevity, the foregoing description employs such terms as "front," "back," "bottom," "top," "side," "height" and the like to designate certain parts of the casing 10 or directions relative thereto. Such designations are made on the basis of the device set up as shown in Figs. 1 to 3 but will be understood as applying to the same parts of the device and relative directions regardless of their 20 orientation with respect to the true horizontal or vertical, and such terms are consistently so used throughout this specification and the subjoined claims.

Variations and modifications may be made 25 within the scope of the claims and portions of the improvements may be used without others.

I claim:

1. A combined portable machine case and folding work stand comprising an open-bottom housing; means on said housing for mounting a machine for movement between operative position extending above the top of the housing and stowed position within the housing; and two support members hinged adjacent the open bottom 40 on opposite sides of said housing to swing towards each other, said support members being of complementary shape, and being so fitted to said housing that when swung against the open bottom of said housing they mesh to form a substantially continuous closure therefor.

2. A combined portable machine case and folding work stand comprising an open-bottom housing; means on said housing for mounting a machine for movement between operative position extending above the top of the housing and stowed position within the housing; and two support members hinged adjacent the open bottom 45 on opposite sides of said housing to swing towards each other, said support members being of complementary shape, and being so fitted to said housing that when swung against the open bottom of said housing they mesh to form a substantially continuous closure therefor, said support members when swung against said bottom lying mainly within the side walls of said housing and forming a surface flush with the bottom edges thereof.

3. A combined portable machine case and folding work stand comprising an open-bottom housing; means on said housing for mounting a machine for movement between operative position extending above the top of the housing and stowed position within the housing; and two support members hinged adjacent the open bottom 55 on opposite sides of said housing to swing towards each other, said support members being of complementary shape, and being so fitted to said housing that when swung against the open bottom of said housing they mesh to form a substantially continuous closure therefor, said support members when swung against said bottom lying mainly within the side walls of said housing and forming a surface flush with the bottom edges thereof.

towards each other to form a closure for said open bottom, the lower edge of the front portion of said housing consisting of a wall element which is readily displaceable to provide space for the knee of the operator when a machine mounted on the stand is in use.

4. A combined portable machine case and folding work stand comprising an open-bottom housing; means on said housing for mounting a machine for hinging movement between operative position extending above the top of the housing, and stowed position swung down within the housing and with its bottom surface adjacent the inside of the back of said housing; two support members hinged adjacent the open bottom on opposite sides of said housing to swing towards each other to form a closure for said open bottom; a work leaf hinged to said housing for movement into a position overlying the top thereof; a releasable tensioning fastener for holding said leaf in said overlying position; and a carrying handle mounted on the front of said housing, the lower edge of the front portion of said housing below said handle consisting of a wall element which is readily displaceable to provide space for the knee of the operator when a machine mounted on the stand is in use.

5. A combined portable machine case and folding work stand comprising a housing; means on said housing for mounting a machine for movement between operative position extending above the top of the housing and stowed position within the housing; two support members hinged at their ends adjacent the bottom on opposite sides of said housing to swing towards each other; at least one foldable brace element connected at one end to one of said support members near its free end, and at its other end to the side of said housing opposite to that on which said one support member is hinged; and a support-separating strut connected to one of said support members near the free end thereof and releasably engageable with the outer support member near the free end thereof.

6. A combined portable machine case and folding work stand comprising a housing; means on said housing for mounting a machine for movement between operative position extending above the top of the housing and stowed position within the housing; two support members hinged at their ends adjacent the bottom on opposite sides of said housing to swing towards each other, each of said support members being substantially as wide as the front-to-back dimension of said housing and each having a front edge and a back edge; at least one foldable brace element connected at one end to one of said support members near its free end, and at its other end to the side of said housing opposite to that on which said one support member is hinged; and a support-separating strut connected to one of said support members near the free end thereof and releasably engageable with the other support member near the free end thereof, said brace element and strut being so constructed and positioned as to be at their connection points no farther than two-thirds of said dimension from either the front edge or back edge of either support member, and so that none of said brace element and strut extends forwardly of a vertical plane generally parallel to said front edges and spaced rearwardly thereof a distance equal to one-third of said dimension, when said support members are in housing supporting position.

7. A combined portable machine case and fold-

ing work stand comprising an open-bottom housing; means on said housing for mounting a machine for movement between operative position extending above the top of the housing and stowed position within the housing, the lower edge of the front portion of said housing consisting of a wall element which is readily displaceable to provide space for the knee of the operator when a machine mounted on the stand is in use; two support members hinged at their ends adjacent the open bottom on opposite sides of said housing to swing towards each other to form a closure for said open bottom, each of said support members being substantially as wide as the front-to-back dimension of said housing and each having a front edge and a back edge; at least one foldable brace element connected at one end to one of said support members near its free end, and at its other end to the side of said housing opposite to that on which said one support member is hinged; and a support-separating strut connected to one of said support members near the free end thereof and releasably engageable with the other support member near the free end thereof, said brace element and strut being so constructed and positioned as to be at their connection points no farther than two-thirds of said dimension from either the front edge or back edge of either support member, and so that none of said brace element and strut extends forwardly of a vertical plane generally parallel to said front edges and spaced rearwardly thereof a distance equal to one-third of said dimension, when said support members are in housing-supporting position.

8. A combined portable machine case and folding work stand comprising an open-bottom housing having a front and back wall and two side walls; means on said housing for mounting a machine for movement between operative position extending above the top of the housing and stowed position within the housing; spaced support members hinged to one side wall and swingable to a non-support position such that their outer surfaces lie flush with the bottom edges of said front and back walls; and support means hinged to the other side wall and so dimensioned and positioned that when the same is swung to non-support position it occupies substantially all of the bottom area not occupied by said support members and its outer surface lies flush with the outer surfaces of said members and the bottom edges of said front and back walls.

9. A combined portable machine case and folding work stand comprising an open-bottom housing having front and back walls and two side walls; means on said housing for mounting a machine for movement between operative position extending above the top of the housing and stowed position within the housing; spaced legs hinged to one side wall and swingable to a non-support position such that one is contiguous with the front wall and the other contiguous with the back wall, and their outer surfaces lie flush with the bottom edges of said front and back walls; and a support panel hinged to the other side wall and so dimensioned and positioned that when said panel is swung to non-support position it fits between said legs and occupies substantially all of the bottom area not occupied by said legs and its outer surface lies flush with the outer surfaces of said legs and the bottom edges of said front and back walls.

10. A combined portable machine case and folding work stand comprising an open-bottom

housing having front and back walls and two side walls; means on said housing for mounting a machine for movement between operative position extending above the top of the housing and stowed position within the housing; spaced legs hinged to one side wall and swingable to a non-support position such that one is contiguous with the front wall and the other contiguous with the back wall, and their outer surfaces lie flush with the bottom edges of said front and back walls; and a support panel hinged to the other side wall and so dimensioned and positioned that when said panel is swung to non-support position it fits between said legs and occupies substantially all of the bottom area not occupied by said legs and its outer surface lies flush with the outer surfaces of said legs and the bottom edges of said front and back walls, the free ends of said legs when in non-support position being flush with the outer surface of said other side wall, the same being notched at its bottom edge to receive said leg ends, said panel having at its free end floor-engaging means the bottom of which is flush with the outer surface of said one side wall when said panel is in non-support position, said one end wall being notched at its bottom edge to receive said means.

11. A combined portable sewing machine case and folding work stand comprising an open-bottom housing having front and back walls and two side walls; means on said housing for mounting a sewing machine for hinging movement between operative position extending above the top of the housing and stowed position swung down within the housing and with its bottom surface adjacent the inside of the back of said housing; spaced legs hinged to one side wall and swingable to a non-support position such that one is contiguous with the front wall and the other contiguous with the back wall, and their outer surfaces lie flush with the bottom edges of said front and back walls; a support panel hinged to said other side wall and so dimensioned and positioned that when said panel is swung to non-support position it fits between said legs and occupies substantially all of the bottom area not filled by said legs and its outer surface lies flush with the outer surface of said legs and the bottom edges of said front and back walls; brace means connected between said legs near the hinged ends thereof; a spacer element connected between said legs near the free ends thereof; a diagonal brace member comprising hingedly connected rigid links connected at one end to said spacer element and at the other end to said other side wall; a separating strut hinged at one end to said panel near the free end thereof and releasably engageable at its other end with said spacer element, said strut being receivable between said legs when the legs and panel are in non-supporting bottom-closing position; a work leaf congruent with the top of said housing and hinged at one edge thereof for movement into a position overlying said top; a releasable tensioning fastener for holding said leaf in said position; and a carrying handle mounted on the front of said housing, the lower edge of said front wall below said handle being readily displaceable to provide space for the knee of the operator when a sewing machine mounted on the stand is in use.

12. A combined portable machine case and folding work stand comprising a housing, the front of said housing defining the front plane of said stand, and the back of said housing the back

plane of said stand; means on said housing for mounting a machine for movement between operative position extending above the top of the housing and stowed position within the housing; and two support members hinged adjacent the bottom on opposite sides of said housing to swing towards each other and against said bottom; a diagonal brace comprising two hingedly connected links pivotally connected at one end near the free end of one of said support members and at its other end to said housing; and a separating strut comprising two hingedly connected links pivotally connected at one end to said other support member near its free end, and releasably engageable at its other end with said one support member near its free end, said brace and strut being so constructed and positioned as to be at their connection points no farther than two-thirds of the front-to-back dimension of said housing from either of said planes, and so that none of said brace and strut extends forwardly of a vertical plane generally parallel to said front plane and spaced rearwardly thereof a distance equal to one-third of said dimension when said support members are in housing-supporting position.

13. A combined portable machine case and folding work stand comprising a housing, the front of said housing defining the front plane of said stand and the back of said housing the back plane of said stand; means on said housing for mounting a machine for movement between operative position extending above the top of the housing and stowed position within the housing; and two support members hinged adjacent the open bottom on opposite sides of said housing to swing towards each other and against said bottom; a pair of flexible diagonal brace members each connected at one end to a side of said housing and at the other end near the free end of that support member hinged to the opposite side of said housing; and a separating strut comprising two hingedly connected links pivotally connected at one end to one of said support members near its free end, and releasably engageable at its other end with the other of said support members near its free end, said flexible brace members and strut being so constructed and positioned as to be at their connection points no farther than two-thirds of the front-to-back dimension of said housing from either of said planes, and so that none of said braces and strut extends forwardly of a vertical plane generally parallel to said front plane and spaced rearwardly thereof a distance equal to one-third of said dimension when said support members are in housing-supporting position.
